WILLIAM W. LASKER AND CHARLES A. MEZGER, OF BROOKLYN, NEW YORK, AS-SIGNORS, BY MESNE ASSIGNMENTS, TO REMINGTON RAND INC., OF NEW YORK, N. Y., A CORPORATION OF DELAWARE.

CONTACT MECHANISM FOR TYPEWRITER-KEY PUNCHES.

Application filed February 10, 1925. Serial No. 8,310.

The present invention relates to electrical contact mechanism and more particularly to such a mechanism employed as an auxiliary terminal control for a key punch circuit control means which is actuated by the operation of a typewriter key.

Some of the objects of the present invention are to provide an improved contact control for punching mechanisms electrically operated selectively by circuits respectively controlled by typewriter keys whereby a maximum operating speed is maintained; to provide a contact mechanism for controlling an electrical circuit whereby the time the circuit is closed is maintained at a minimum for operating purposes; to provide a circuit control for a typewriter key punch whereby selection and operation of a key partially closes a circuit and thereafter the circuit is automatically completed by an agency operated by the typewriter; to provide an improved circuit control wherein burning and damage to electrical contacts is eliminated; and to provide other improvements as will hereinafter appear.

In the accompanying drawings, Fig. 1 represents a side elevation of one form of contact mechanism embodying the present invention; Fig. 2 represents a front elevation of the same; Figs. 3, 4, 5 and 6 represent respectively parts details; Fig. 7 represents a plan of the mechanism; and Fig. 8 represents an illustrative circuit showing the contact mechanism of the invention.

Referring to the drawings, one form of the present invention is shown as applied to a typewriter of standard construction, and is arranged to be operated by the escapement wheel 10, of such typewriter. The invention generally applies to the closing of an electrical circuit after such circuit has been selected and closed at one part by the operation of a selected typewriter key, and the complete closing of the circuit results in the selection of a card punch corresponding to the key operated. Thus there are a plurality of punches, a plurality of typewriter keys, and a plurality of electrical circuits, (a combination of the keys and circuits making it possible to employ, if desired, a less number of punches than there are typewriter keys) and the present invention per-

tains to the closing of the selected circuit for operation. In Fig. 8 two circuits 11 and 12, with a common return, two punches 13 and 14 operated respectively by solenoids 15 and 16, and three typewriter keys 17, 18 and 19, are shown as illustrative of the application of the invention to a typewriter key punch system.

As here shown the operation of the key 17 brings the contactor 20 and contact 21 together to partially close the circuit which includes solenoid 15, while the operation of key 18 brings contactor 22 and contacts 23 and 24 together to partially close both circuits and upon final closing both solenoids 15 and 16 will be energized, and the operation of key 19 will bring contactor 25 and contact 26 together to partially close the circuit of solenoid 16 at one point so that if closed at another the solenoid will be energized for operation. These circuits have a common battery or source of current 27, a switch 28 for rendering both circuits inoperative at will, and a rheostat 30 for controlling the amount of current in the respective circuits. This switch 28 and rheostat 30 are located in the common return conductor 31 of the two circuits and this common return conductor 31 is broken to provide an auxiliary contact 32 and an auxiliary contactor 33, this arrangement insuring each circuit being maintained open after a selected typewriter key has been operated until the contactor 33 comes into engagement with the contact 32. It is to be understood that the auxiliary control by contact 32 and contactor 33 is in the common return for a plurality of circuits so that while there may be as many circuits as there are keys on the keyboard of a typewriter, each circuit will be finally completed by this auxiliary control. For the purpose of mounting this auxiliary control in operative make and break relation, the contact 32 is carried by the end of a screw 34 threaded into a support 35 of hard rubber or other insulating material, which is carried by a bracket 36 arranged to be supported upon the frame of the typewriter so that the contact control parts may be properly held in operative relation to the escapement wheel 10 of the typewriter. The return conductor 31 has

55 60 65 70 75 80 85 90 95 100

its terminal 37 clamped to the screw 34 by a nut 38 or other binding means. The contactor 33 is mounted in juxtaposed relation to the contact 32 upon a flexible conducting strip 40, which is secured through the medium of a hard rubber piece 41 to a member 42 pivoted upon a rock spindle 43. This member 42 is provided at one side with an extension hook 44 to receive one end of a spring 45, while the lower extremity of the member 42 is also provided with a hook 46 to receive one end of a coil spring 47. This latter spring has its opposite end connected to a fixed pin 48 suitably connected to the bracket 36, and the normal tendency of the spring 47 is to cause the member 42 to turn in a clockwise direction, as seen in Fig. 2. The action of the spring 47, therefore, is to break the contact of the contactor 33 at the proper time. The contactor strip 40 is connected to the other end of the return conductor 31, as will be understood.

In order to move the contactor strip 40 to bring the contactor 33 against the contact 32, the coil spring 45, which is connected at one end to the hook 44 of the member 42, is connected at its opposite end to a trigger 50, which has a depending arm 51 located in close proximity to the body of the member 42. This trigger 50 is rigidly connected to the spindle 43 and its arm 51 rests under spring tension against a stop lug 52 projecting laterally from one side of the member 42. Thus, a counterclockwise rocking of the spindle 43 will be transmitted through the trigger 50 and spring 45 to the member 42, and the latter is swung counterclockwise to bring the contactor 33 against the contact 32, but if there is any continued movement of the spindle in the same direction after the contact has been made, the spring connection between the trigger 50 and arm 44 will permit the former to move without moving the latter.

In order to transmit motion to the spindle 43, it has keyed or otherwise rigidly fastened thereon, a trip 53, which projects into the path of the teeth of the escapement wheel 10, its length being such that it extends approximately to the pitch line of the teeth of the escapement wheel, so that when the latter is stationary, as shown in Fig. 2, the trip 53 will extend between two adjacent teeth and rest in engagement with one of said teeth through the action of the spring 45. When the escapement wheel 10 is operated to move an angular distance of one tooth, it therefore carries with it the trip 53 and transmits motion to the spindle 43, so that the latter rocks the trigger 50 and causes the spring 45 to pull the pivoted member 42 in a direction to bring the contactor 33 against the contact 32 and thus complete the circuit.

Where a key punch selecting circuit is 65 completely closed by a single contact under the control of a typewriter key, the length of time such key is held down plays an important part in the proper and continuous operation of the system, and when operators 70 unduly prolong the contact by holding the typewriter key down longer than necessary the contacts are soon burned away and the system is rendered highly inefficient. It is an object of the present invention to remove 75 the circuit control from the operator of the typewriter and provide a means whereby all circuits selected will be closed for the same length of time and that interval just sufficient to insure the actuation of the device 80 under electrical control.

In the form of the invention here described, the manual actuation of typewriter key 17 causes the contactor 20 to be brought against contact 21 and thus close one open part of the circuit 11. The operation of the key 17 actuates the selected type bar of the typewriter and releases the escapement wheel 10 so that the typewriter carriage automatically moves one letter space, 90 as will be understood. This movement of the escapement wheel 10 is transmitted to the trip 53 which travels with the aforesaid wheel until the wheel tooth in engagement with it moves beyond the arc of 95 contact, whereupon the trip 53 is released and automatically swings back to its former position but in engagement with the next tooth of the wheel. The movement of the trip 53 is transmitted through the spindle 100 43 to the trigger 50, which thereupon is swung counterclockwise to place tension upon the spring 45 to rock the member 42 and cause the strip 40 to bring the contactor 33 against the contact 32. This completes 105 the circuit 11 so that the solenoid 15 is energized to select the punch 13 which corresponds to the key 17. The circuit 11 is only closed while the escapement wheel 10 is making a step movement and is broken by the 110 trip 53 being released from the tooth which has picked it up during a step movement of the wheel. As soon as the trip 53 is released, the spring 47 breaks the contact by pulling the member 42 in a direction to return the contactor 33 to its non-contact position, and the spring 45 causes the trip 53 to snap back into the path of the next tooth of the wheel 10 preparatory to the 115 next type key action. In this way the punch control circuits are all closed for the same length of time and it makes no difference whether the type key contact is made a long or short one. In other words, the make and break of the circuit take place automatically 120 instead of manually, and the time the circuit is closed is out of the control of the operator of the typewriter.

While only a single form is shown in which this invention may be embodied, it is to be understood that the invention is not limited to any specific construction, but 5 might be applied to various forms without departing from the spirit of the invention or the scope of the appended claims.

Having thus described our invention, we claim:

10 1. In a typewriter key punch mechanism, the combination of a punch, electrical means for operating said punch, a circuit including said means, keys for operating a typewriter, a contact means controlled by one of said 15 keys for partially closing said circuit, and contact means automatically operated for completing the closing of said circuit.

20 2. In a typewriter key punch mechanism, the combination of a punch, electrical means for operating said punch, a circuit including said means, keys for operating a typewriter, a contact means controlled by one of said keys for partially closing said 25 circuit, and contact means operated by a part of said typewriter other than said key for completing the closing of said circuit.

30 3. In a typewriter key punch mechanism, the combination of a punching mechanism arranged to be controlled from a typewriter, an electric means for operating said punching mechanism, a circuit including said means and normally open at two places, keys for said typewriter, contact means respectively controlled by said keys for closing 35 one place in said circuit, and contact means automatically operated for closing the other place in said circuit.

40 4. In a typewriter key punch mechanism, the combination of a punching mechanism arranged to be controlled from a typewriter, an electric means for operating said punching mechanism, a circuit including said means and normally open at two places, keys for said typewriter, contact means respectively controlled by said keys for closing one 45 place in said circuit, and contact means operated by a part of said typewriter other than said key for closing the other place in said circuit.

50 5. In a typewriter key punch mechanism, the combination of a punching mechanism arranged to be controlled from a typewriter, an electric means for operating said punching mechanism, a circuit including said means and normally open at two places, means controlled by the keys of said typewriter for closing one place in said circuit, and means operating automatically after 55 said first closing means to complete the closing of said circuit at the other place.

60 6. In a punching mechanism, the combination of a punch, electric means for operating said punch, a circuit including said means, said circuit being normally open at

two places, manually controlled means for closing said circuit at one place, and automatic means for closing said circuit at the other place, whereby said punch is operated.

7. In a punching mechanism, the combination of a plurality of punches, separate electric means for operating said punches, normally open circuits including said means and having a normally open common return, keys for respectively closing said circuits in 75 part and simultaneously operating a typewriter, and means actuated by a step-by-step movable part of said typewriter for closing said common return, whereby any circuit closed by a key is completed to actuate the punch operating means controlled by the closed circuit.

8. In a punching mechanism, the combination of a plurality of punches, separate electric means for operating said punches, 85 normally open circuits including said means and having a normally open common return, keys for respectively closing said circuits in part and simultaneously operating a typewriter, and means including a step-by-step 90 movable part of the escapement of said typewriter for closing said common return, whereby any circuit closed by a key is completed to actuate the punch operating means controlled by the closed circuit.

9. In a typewriter key punch mechanism the combination of a punch, electrical means for operating said punch, a circuit including said means, keys for operating a typewriter, a contact closed by initial movement 100 of one of said keys for partially closing said circuit, and a contact closed automatically as an incident to continued movement of the key for completing the closing of the circuit.

10. In a typewriter key punch mechanism, the combination of a punch, electrical means for operating said punch, a circuit including said means, keys for operating a typewriter, a contact closed by initial movement of one 110 of said keys for partially closing said circuit, and a contact closed automatically as an incident to subsequent continued movement of the key for completing the closing of the circuit before the termination of movement of the key.

11. In mechanism of the character described, the combination of a keyboard comprising a plurality of keys, a recording element appropriate to each key, a solenoid for each recording element for causing it to function, a normally open circuit for each key and its corresponding solenoid, means for selecting a circuit by depression of a key, and automatically operable means 120 for closing and opening the selected circuit.

12. In mechanism of the character de-

scribed, the combination of a keyboard comprising a plurality of keys, a punch element appropriate to each key, a solenoid for each punch element for causing it to function, 5 a normally open circuit for each key and its corresponding solenoid, means for selecting a circuit by depression of a key, and auto-

matically operable means for closing and opening the selected circuit.
